UNITED STATES PATENT OFFICE.

VINCENT WALENTOWICZ AND ANDREW SEMRAU, OF MILWAUKEE, WISCONSIN.

STOCK-FOOD COOKER.

Application filed November 21, 1921. Serial No. 516,706.

To all whom it may concern:

Be it known that we, VINCENT WALENTOWICZ and ANDREW SEMRAU, both Polish subjects who have filed applications for citizenship in the United States, and residing in the city of Milwaukee, county of Milwaukee, and State of Wisconsin, have invented certain new and useful Improvements in Stock-Food Cookers; and we do declare the following to be a clear, exact, and complete description thereof, such as will enable persons skilled in the art to which the invention relates to make and use the same, reference being had to the accompanying drawing for an illustration of one form in which our invention has been embodied.

The invention relates to a cooker designed for preparing at one time a large amount of food to be fed to stock.

The invention comprises an open topped fire pot which is adapted to receive and support a large kettle or caldron containing the food to be cooked. The caldron is provided with pivoted bearings whereby it may be lifted from its seat upon the fire box, and when so lifted may be tilted to a horizontal position to facilitate the removal of the cooked contents therefrom.

Devices for sealing the caldron during the cooking operation, and for lifting the caldron from its seat from the fire box, and for holding the caldron in its tilted or horizontal position, are embodied as parts of the structure.

The novel features of the invention will be pointed out in the appended claims.

The drawings which accompany this specification show the invention in a simple structural form, such as will easily be understood. In such drawing,

Figure 1 is a view in elevation of our improved cooker, the details of construction of which will be described later.

Figure 2 is a view in elevation, with parts broken away for the sake of clearness, and showing the construction of the caldron, separate from the fire box.

Fig. 3 is a view partly in elevation and partly in section showing some of the features of construction of the fire box.

Fig. 4 is a detail of the clamping mechanism employed for sealing the caldron.

In the drawings the numeral 10 indicates the base member of our improved cooker, such base member being constructed as a fire box of any suitable form which will adapt

it for the purposes intended. The fire box 10 is provided with a grate 11, a stoking door 12 and is connected with a flue 13. A baffle plate 14 may be arranged at the rear 60 of the compartment in which the fuel is placed, and over which baffle plate the smoke and gases from the fire box will pass out through the flue 13.

The base member 10 is preferably of circular form in horizontal section, and is open at the top to permit the free passage of the heat to the caldron which is placed over the said opening. An annular ledge 15 is formed about and slightly below the opening in the top of the base member, the purpose of said ledge being to provide a recessed seat for the caldron.

The caldron 16 is a tubular member, open at the top and closed at the bottom. Around the caldron and on a line about midway of its length, a ring 17 is secured, and from this ring depends a skirt or apron 18 extending to a distance approximately in the horizontal plane of the bottom of the caldron. The 80 lower edge of the said skirt or apron 18 is adapted to be snugly seated on the annular ledge 15 in the top of the fire box, so as to prevent the escape of the heat generated in the fire box.

Standards 19 and 20, rise from opposite sides of the fire box, and carry at their upper ends horizontal studs 21 and 22. On opposite sides of the caldron and near the horizontal plane of the ring 17, studs 23, one 90 of which is shown, are affixed in the skirt or apron 18. A bail 24 is pivoted at its free ends upon the said studs 23, the said bail being notched near its pivotal points, as at 25. The notches 25 are adapted to receive the 95 studs 21 and 22 projecting inwardly from the standards 19 and 20, and when downward pressure is applied to the bail as a lever, the studs 21 and 22 form the fulcrum upon which the caldron may be lifted from its seat within the recess in the top of the fire box. When the bail 24 has been lowered into the dotted line position indicated in

Fig. 1, a hook 26 pivoted on the standard 20, may be engaged with a stud 27, projecting 100 from one leg of the bail, so that the caldron will be held in its elevated position, free from its place of rest upon the fire box. Antifriction disc rollers 28 may be placed on the studs 23 outside of the ends of the 110 bail, and in the downward movement of the bail, the said disc rollers will travel around

the studs 21 and 22, as indicated in Fig. 1. A handle 29 is attached to one side of the caldron and extends longitudinally thereof to some distance above the same, the 5 said handle providing a convenient means whereby the caldron may be rotated into its horizontal position after having been lifted from its seat upon the fire box. A chain 30 attached at one end to the base 10 member 10 and having a hook at its other, may be engaged with the handle 29 to hold the caldron in the desired position for permitting the removal of the cooked contents thereof, and preventing the reverse rotation 15 of the caldron as the center of gravity shifts with the removal of the contents. Upon the opposite side of the caldron, a notched member 31 is attached, the notch 32 thereof being open at one side for a purpose to be 20 described.

A lid 33 is adapted to close the open top of the caldron, the said lid resting within an annular groove so as to make a good joint. In the plane of the notch 32, an 25 opening 34 is formed in the handle 29. One end of a crown piece 35 is adapted to be inserted in the opening 34, the other end of such crown piece being moved laterally into the notch 32 of the catch 31. A screw 36 30 passes centrally through the crown piece and is adapted to exert pressure upon the lid 33 to hold the same firmly in position upon the caldron.

Within the caldron is located a separator 37, having a bottom plate and an upstanding hollow stem both perforated to permit the circulation of water during the cooking operation. The separator is spaced a slight distance from the bottom of the caldron, so 35 as to accommodate a small quantity of water and prevent scorching of the food in cooking by a too direct application of the fire. The distance of the skirt or apron 18 from the bottom of the caldron by means of the 40 ring 17, provides a space about the caldron which may be entered by the heat and facilitate the cooking operation. A steam vent 45

38, provided with a hinged valve cap 39 is placed near the mouth of the caldron. Handles 40 may be affixed to the lid 33, as 50 a convenience.

In operation, the caldron is seated upon the base member or fire box 10, as shown in Fig. 1, and is then filled with the desired amount of food which is to be cooked, a 55 proportionate quantity of water being then poured into the caldron. The lid 33 will be clamped in position and a suitable fire will effect the cooking. When this has been completed the caldron will be tilted as herein- 60 before described, and the lid 33 will be removed. The caldron is now in position for the convenient removal of the contents thereof. By reason of the dimensions of the apparatus, the provisions for tilting the 65 caldron to permit the removal of the cooked contents, has proven very advantageous.

Modifications in the structure may be made without departing from the spirit of 70 our invention.

Having thus described our invention, what we claim and desire to secure by Letters Patent of the United States, is:

In a stock food cooker, a base constructed as a fire box with a depressed seat in the 75 top thereof, a caldron provided with a skirt or apron resting in the said seat and providing space at the sides of the caldron for the application of heat in the cooking operation, means for lifting the caldron clear 80 of its seat, such means including pivoted supports for the caldron, whereby the latter may be turned to render its contents accessible, and means for retaining the caldron in such turned position. 85

In testimony whereof we have signed our names at Milwaukee this 19th day of November, 1921.

V. WALENTOWICZ.
A. SEMRAU.
